[57] CLAIM

The ornamental design for a candy bouquet display, as
shown and described.

DESCRIPTION

FIG. 1 is a front perspective view of a candy bouquet display
showing my new design;

FIG. 2 is a top perspective view thereof; and,

FIG. 3 is a bottom, front perspective view thereof, the back
and sides of the body of the display being identical.

The basket is shown in broken lines for illustrative purposes
only and forms no part of the claimed design.
